ANNEALING FURNACE AND METHOD OF
ANNEALING

Edward I. Huff, Pittsburgh, Pa.

Application October 22, 1937, Serial No. 170,332

3 Claims. (Cl. 263—52)

My invention relates to the annealing of metal, and consists in an annealing furnace and a method of operation, particularly adapted to the annealing of flat sheets of steel. The objects are economy in furnace construction and in operation, and excellence of product.

The invention is illustrated in the accompanying drawings. Fig. I is a view of a furnace of the invention, partly in plan from above and partly in horizontal section; and Fig. II is a view of the furnace in vertical section and to larger scale, the plane of section being indicated at II—II in Fig. I.

Referring to the drawings, the furnace is of muffe type and includes an outer heat-insulating wall 1 and roof 10, and an inner heat-conducting muffe 2. The muffe is a thin-walled shell of metal. It is spaced from the side walls and roof of the furnace, and in such space the heat-affording flames may be developed. Within the muffe 2 the material to be treated is enclosed.

In modern practice ingots and billets of steel are reduced in continuous operation to highly attenuated sheets. On the completion of the rolling operation, the sheets, trimmed to particular size or not, are arranged in stacks and subjected to the requisite annealing operation.

The operation of annealing consists in heating the material to a peak temperature and cooling it again; and, while rate of heating, peak temperature, time at peak, and rate of cooling must, in order to attain desired results, conform to a certain standard, there is a margin of tolerance; and if throughout all its extent each sheet in its treatment be brought within such margin, the product will be of uniform quality. In the operation of the furnace of my invention the material is so brought within the margin of tolerance, and the annealed product is of uniform and standard quality.

The muffe 2 is of usual structure in that it consists of integral and imperforate side and top walls, is open at bottom, and is adapted to rest upon a horizontal base, enclosing the material to be treated—a stack of sheets S in this case. The proportioning of the muffe to the stack is a matter that admits of variation, and it will be understood that in such particulars the showing is exemplary merely.

The muffe in the assembly rests upon a pan 3, and the pan 3 horizontally upon the hearth 4 of the furnace. The pan is doubly flanged at its margin (cf. double flange 30), and the lower edge of the muffe engages the bottom of the pan 55 between these flanges, and luting L is applied, as

shown in Fig. II. A rectangular block 5, arranged within the margins of pan 3, may afford support for a rectangular stool 6, upon which the charge S immediately rests.

In usual way conduits 40 may extend through 5 the hearth and open into the enclosure beneath the muffe, for introducing and removing gases, to establish and maintain desired atmosphere around the sheets S.

The all-inclosing outer wall of the furnace consists in a box-like hood, constructed essentially of heat-insulating brick, externally braced and reinforced by means of structural steel. Otherwise closed, it is open at bottom, and is applicable to and removable from the stationary and horizontally extending hearth 4. The walls of insulating material are built within a supporting shell 11 of sheet metal, and this shell of metal, extending downward, enters a channel 110 formed in the hearth, wherein luting LL is provided (Fig. II). 10 As shown, the box-like hood is provided with a perforate lug 22, for the attachment to it of raising and lowering mechanism. 20

When the movable parts of the furnace are assembled over the pack of sheets S seated on the hearth-stool 6, there is, as has been said, a space between the walls of the muffe 2 and the walls 1, 10 of the hood. In accordance with the invention, the spaces or regions C, C between the opposite side walls of the muffe and the side walls of the hood are employed as the primary, if not the sole, combustion chambers for the fuel. Burners 7 are arranged in each of the opposite end walls of the elongate and relatively narrow hood; in service these burners direct burning columns of fuel and air into the regions C, C; in each of the elongate and relatively narrow regions C, C on opposite sides of the muffe 2 the burning columns are directed inward, toward the vertical mid-plane of the furnace, and the walls of muffe are 30 heated. Observation ports 8 may be provided in the walls, above the burners. 35

Each of the opposite side walls 1 of the hood includes a series of flues 9 that, extending vertically, open at their upper ends into horizontal 45 stack-flues 90, embodied in the upper refractory body or roof of the hood. And each flue 90 opens into the atmosphere by way of an outlet 99 which may comprise a short stack, or be connected to a relatively tall stack. The hearth 4 includes a 50 series of transverse flues 12 that establish communication between the combustion zones C, C and the side-wall flues 9. Each hearth flue 12 opens at one end upward through the floor of the hearth 4 into the combustion zone or region C 55

on one side of the muffle 2, and, extending from such opening through the body of the hearth, communicates at its opposite end with one of the vertical wall flues 9. The arrangement of flues 12, 9 is staggered; that is, one flue 12 opens into the region C on the left-hand side of the muffle 2 and extends to a flue 9 in the right-hand side wall of the hood, while the next adjacent flue 12 extends from the region C on the right of the muffle to a flue 9 in the left hand wall of the hood. Thus, a system of hearth flues, arranged in spaced-apart relation longitudinally of the furnace, interconnects the combustion zones C with the flues in the opposite side walls of the hood.

15 It will be perceived that the burners 7 are located below the horizontal mid-plane of the furnace, with the consequence and effect that the flames, springing from the opposite ends of the regions C, sweep horizontally, adjacent to the hearth of the furnace, toward the centers of such regions C. In the operation of the furnace, the horizontally flowing columns of burning fuel and hot gases are drawn downward into the mouths of hearth flues 12, that are spaced longitudinally of the course of flow. Straying streams of hot gases, meandering upward over the side walls of the muffle and spreading laterally over its end walls, meet and mingle over the top wall of the muffle and beneath the closed roof 10 of the hood, 20 and these idly meandering streams distribute heat, by conduction and convection, to the upper side, end and top walls of the muffle. The main bodies of the burning fuel and hot products of combustion are drawn immediately from the regions C, C into the flues 12, and are led transversely through the hearth and introduced to the flues 9 in the side walls of the hood, whence the hot gases rise into the horizontal flues 90 and 25 exit by way of stacks 99.

30 40 The heat thus generated in the furnace is concentrated immediately above and within the hearth upon which the charge S is seated, and the heat given up to the side walls 1 of the hood so far augments the insulating and refractory 45 capacity of these walls that conduction and convection of heat over and through the upper walls of the muffle, and conduction of heat immediately from the hearth to the base of the charge, become effective to elevate and hold all portions of 50 the charge at desired temperature. The requisite heating of the charge is obtained rapidly and with uniformity throughout the entire charge. In such operation of the furnace the method of my invention is practiced, and by virtue of the 55 structure described I achieve advantages in a hood-type furnace that hitherto were only realized, if realized at all, in a stationary furnace of large and costly construction.

An important detail of construction remains for 60 consideration. It will be perceived that the base of the hood fits over and peripherally encompasses the upper body portion of the hearth 4. Each flue 12, opening upward at one end through the floor of the hearth, as already mentioned, 65 terminates at its opposite end in the side surface of the hearth which is embraced by the basal wall portion of the hood. There is a clearance 20 (Fig. II) between the body of the hearth and such basal wall of the hood, and into this clearance the 70 lower ends of the wall flues 9 of the hood open and communicate with the hearth flues 12. Thus,

while precise registry of flues 9 and 12 may be effected, it is not required. The luting LL seals the clearance 20 from the outer atmosphere, while the wall of the hood carries a continuous shoulder 21 that overlies the upper peripheral corner of the hearth and blanks direct communication between the clearance 20 and the combustion chambers C, C within the furnace. Thus, the desired organization of hearth and side wall flues is permissible in a furnace of the removable hood type. 10

I claim as my invention:

1. The herein described method of operating a hood-type annealing furnace including a stack of metal sheets seated upon the furnace hearth and enclosed within a muffle, which method includes introducing burning columns of fuel into the regions between muffle and the opposite side walls of furnace hood, drawing the burning fuel and products of combustion on opposite sides of the muffle downward from the course of fuel delivery, and, while some of the burning fuel and hot products meander upward on opposite sides of the muffle and meet and mingle over the top of the muffle and under the roof of the furnace hood, leading the downwardly drawn products transversely through the hearth upon which said stack of sheets is seated, and then removing such products upward through the side wall of the hood which lies on opposite side of the muffle from that from which said products enter said hearth. 30

2. An annealing furnace including a hearth for supporting the material to be annealed, a muffle enclosing the material on the hearth, and a hood applicable to and removable from said hearth, said hood having refractory side walls spaced from the walls of said muffle, means for introducing burning columns of fuel into the regions between the side walls of said hood and said muffle, flues in the opposite side walls of said hood, flues extending transversely through said hearth, certain of said hearth flues communicating with the region of combustion on the right-hand side of said muffle and extending to and opening into the flues in the left-hand side wall of said hood, and other of said hearth flues establishing communication between the combustion region on the left-hand side of said muffle and the flues in the right-hand side wall of said hood. 45

3. An annealing furnace including a hearth for supporting the material to be annealed, a muffle enclosing the material on the hearth, and a hood applicable to and removable from said hearth, said hood having refractory side walls spaced from the walls of said muffle, means for introducing burning columns of fuel into the regions between the side walls of said hood and said muffle, flues in the opposite side walls of said hood, flues extending transversely through said hearth, certain of said hearth flues communicating with the region of combustion on the right-hand side of said muffle and extending to and opening into the flues in the left-hand side wall of said hood, and other of said hearth flues establishing communication between the combustion region on the left-hand side of said muffle and the flues in the right-hand side wall of said hood, into which stack-flues said flues in the side walls of said hood open. 65

EDWARD I. HUFF.
